UNITED STATES PATENT OFFICE

161,030

ELECTRICAL BINDING-POST TERMINAL

Henry C. Littlejohn, Lexington, Mass., assignor
to General Radio Company, Cambridge, Mass.,
a corporation of Massachusetts

Application July 14, 1949, Serial No. 3,918

Term of patent 14 years

(Cl. D26—1)

To all whom it may concern:

Be it known that I, Henry C. Littlejohn, a citizen of the United States, residing at Lexington, Massachusetts, have invented a new, original, and ornamental Design for Electrical Binding-Post Terminal, of which the following is a specification, reference being had to the accompanying drawings, forming a part thereof.

In the accompanying drawings, Fig. 1 is a perspective view of an electrical binding-post terminal, showing my new design, and Figs. 2 and 3 are respectively side and end elevations of the same.

I claim:

The ornamental design for an electrical binding-post terminal, substantially as shown.

HENRY C. LITTLEJOHN.
